(57) **CLAIM**

The ornamental design for a hood for a vehicle, as shown and described.

DESCRIPTION

FIG. 1 is a perspective view of a hood for a vehicle, showing our new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

Stippling and tangency lines in the drawings represent the three-dimensional contours of the design, and are not intended to indicate surface decoration. The broken lines shown in the drawings depict portions of the hood for a vehicle in which the design is embodied that form no part of the claimed design.
